ROLLER DIE

John W. Offutt, Ellwood City, Pa., assignor to
 National Tube Company, a corporation of New
 Jersey

Application April 26, 1946, Serial No. 665,168

2 Claims. (Cl. 80—12)

1

This invention relates to metal reducing dies having cam-positioned rolls for effecting the desired reductions. Such dies are preferably used for reducing tubing telescoped over a supporting bar or mandrel.

It is an object of the present invention to produce light-walled hot, or cold-rolled tubing.

It is a further object to produce tubing having a high D/T ratio.

The foregoing and further objects, together with the principles and method of operation of the invention, will be apparent from the following description and drawings, in which:

Figure 1 is a vertical longitudinal section of the die of my invention showing a tubular workpiece and mandrel disposed therein;

Figure 2 is an end elevation in the direction of the arrow and partly in section, showing the working pass;

Figure 3 is an enlarged detail of a portion of the pass; and

Figure 4 is an enlarged detail on line IV—IV of Figure 3.

Referring more particularly to the drawings, the numeral 2 designates a mandrel on which there is telescoped a tubular workpiece 4 disposed in the pass of the die 6 of my invention.

The die is composed of a circular housing 10 having a central opening 12 and a series of radially disposed longitudinally extending T-shaped tapered slots 14.

Small, trunnion-shaped, working rollers 16 having flat work-engaging faces 18, are disposed in segmental holders 20 which are held together by cap screws 22.

The holders 20 are T-shaped in cross section so as to fit in the T-shaped slots 14. These holders have a channel 23 with oppositely disposed circular grooves 24 adjacent the outer edge throughout a large portion thereof to provide a guideway for the rollers, due to the trunnion-like extensions thereof being disposed in these grooves. On the inner side of the holders 20, that is, the side adjacent the pass, there are cams 26 having surfaces 28 which provide backing surfaces for the rolls 16. The surfaces 28 are parallel to the pass line and have curved ends 30 which are shaped to guide the rollers into and receive them from the guideway formed by the grooves 24. The diameter of the rollers and the guideway provided by grooves 24 and cams 26 are proportioned so that the rollers substantially fill such space with a minimum of loss motion therebetween, so that the roller entering the work zone will follow the preceding roller rather

15 closely. Guides 32 are provided in the inner portions of the holders to hold the rollers in position and alignment when there is no workpiece in the die. The face of the rollers and cams is flat so that line contact therebetween may be maintained.

10 The holders 20 are secured and positioned within the housing 10 by a split ring 34 mounted on the housing by bolts 36.

15 The housing 10 is mounted in a die holder on either a conventional draw or push bench after the rollers and holders are positioned and secured therein.

20 In operation, the bar or mandrel 2 with the tube 4 is pushed into the die until the workpiece engages the rollers at the entering end of the cams. As the rollers advance and squeeze the workpiece between the mandrel and the rollers, the wall of the tube is reduced and all rollers 20 ahead and behind the rollers in contact with the work, are pushed along their guideways so that one after another they come into working position.

25 Figure 4 indicates the action that takes place as the work progresses through the die. It will be noted on the entering end, the first roll moving over the curved end 30 of the cam 26 has just made contact with the workpiece 4 and that there is an unreduced section of tubing between the first and second roller, but that this section 30 is reduced by the second roller as the tube progresses through the die. At the same time, the first roller is reducing its section. The backing up or straight surface 28 of the cam which is 35 parallel to the axes of the bar and workpiece must be long enough to iron out any high spots left on the outside of the workpiece by the earlier action of the rollers.

40 It should be noted that the workpiece will move along the bar as it elongates the wall reduction, with the result that the bar moves faster than the unreduced section of the workpiece. As shown in Figure 3, there is a side flow of metal 45 between the rollers which acts to lift the sections of the workpiece between the adjacent rollers in such a way that the workpiece is somewhat loose on the bar, and thereby permits relative movement between the bar and the workpiece without excessive friction and resistance. This 50 becomes of great importance when the workpiece is pushed through a series of dies as in such case there is a substantial longitudinal movement of the workpiece on the bar between and within the dies, which would not be possible if the tube 55 were tight on the bar.

A further advantage of the freedom of the metal to side or peripheral flow, is that it assists in the correction of eccentricity or variation in the wall thickness of the workpiece. This correction of wall thickness is due to the fact that the thick side of the tube will offer less resistance to deformation than the thin side due to variation in temperature in the case of hot drawing or work hardening in the case of cold drawing. That is in hot drawing, the thin sections will be cooled more than the thick sections and therefore offer more resistance to deformation, and in cold work the thin sections will be hardened throughout quicker than the thicker sections.

While the lengthening of the tube tends to reduce the sections between the rollers by a stretching action, one pass through the die leaves substantially unreduced portions where not contacted by the rollers. This will in all cases necessitate the workpiece being simultaneously drawn or pushed through a series of dies. As shown by dotted lines in Figure 3, the successive dies should be disposed so that the mid-portion of their rollers engage the ribs left by the preceding die.

The die of my invention has the particularly beneficial result of requiring less power for a given amount of reduction than other ways of reducing annular sections since the work rollers are of small diameter and accordingly the arc of contact is small. Moreover, since the rolls travel with the workpiece, sliding friction is eliminated. This die also has the advantage that it can be used on either hot or cold workpieces and lastly thinner-rolled hot-rolled tubing can be produced than was heretofore economically feasible.

While I have shown and described one specific embodiment of my invention, it will be understood that this embodiment is merely for the purpose of illustration and description and that various other forms may be devised within the scope of my invention, as defined in the appended claims.

I claim:

1. A reducing die for tubular members having an inlet and an outlet side, said die comprising a cylindrical housing having a concentric opening therethrough, said housing having a plurality of equally spaced, longitudinally extending, T-shaped slots extending therethrough, said T-shaped slots comprising head and leg portions, the leg portions being radially disposed and the head portions transversely disposed of said housing, the legs of said slots opening into the interior of said annular housing and being of decreasing length, the head portions thereof gradually converging toward the outlet side of said die, an annular ring member mounted transversely of said die on the outlet side there-

of and extending into the concentric opening of said housing, T-shaped holding members comprising leg and head portions, said members being slidably disposed in said T-shaped slots, each of said holding members being interiorly grooved to form a roller guideway, a plurality of rollers disposed in said roller guideways, backing-up cams disposed between said guideway and the inner faces of said holding members, the backing-up cams of said holders combining to define an elongated substantially circular reducing pass, said T-shaped holders abutting said ring, and means for adjusting the position of said ring to vary the size of said reducing pass.

2. A reducing die for tubular members having an inlet and an outlet side, said die comprising a cylindrical housing having a concentric opening therethrough, said housing having a plurality of equally spaced, longitudinally extending, T-shaped slots extending therethrough, said T-shaped slots comprising head and leg portions, the leg portions being radially disposed and the head portions transversely disposed of said housing, the legs of said slots opening into the interior of said annular housing and being of decreasing length, the head portions thereof gradually converging toward the outlet side of said die, an annular ring member mounted transversely of said die on the outlet side thereof and extending into the concentric opening of said housing, T-shaped, longitudinally split, holding members comprising leg and head portions, said members being slidably disposed in said T-shaped slots, each of said holding members being interiorly grooved to form a C-shaped roller guideway, the ends of which extend to the surface of the inner end of the leg portion, a plurality of rollers disposed in said roller guideways, means extending inwardly from said holders for guiding said rollers across the inner face of said holders, backing-up cams disposed between said inwardly extending guiding means and the inner faces of said holding members, the backing-up cams of said holders combining to define an elongated substantially circular reducing pass, said T-shaped holders abutting said ring, and means for adjusting the position of said ring to vary the size of said reducing pass.

JOHN W. OFFUTT.
